P. J. LUNATI

LIFTING DEVICE FOR MOTOR VEHICLES

Filed Nov. 28, 1924

Inventor:
Peter J. Lunati,
By John H. Farley,
Atty.

UNITED STATES PATENT OFFICE.

PETER J. LUNATI, OF MEMPHIS, TENNESSEE.

LIFTING DEVICE FOR MOTOR VEHICLES.

Application filed November 28, 1924. Serial No. 752,527.

To all whom it may concern:

Be it known that I, PETER J. LUNATI, a citizen of the United States, residing at Memphis, in the county of Shelby and State 5 of Tennessee, have invented certain new and useful Improvements in Lifting Devices for Motor Vehicles, of which the following is a full, clear, and exact specification.

My invention relates to lifting devices for 10 motor vehicles. The principal object of the invention is to provide a device whereby a vehicle may be elevated above the ground to permit ready access to the mechanism carried by the under body by a garage mechanic for the purpose of repairing and 15 cleaning the vehicle and to provide a construction of this kind which is compact and will occupy comparatively small space and may be readily operated by fluid pressure 20 supplied from a convenient source.

With this object and others in view, my invention is embodied in preferable form in the device hereinafter described and illustrated in the accompanying drawings.

25 In these drawings—

Fig. 1 is a central vertical section;

Fig. 2, a top plan view; and

30 Figs. 3 and 4 are plan and side views respectively of the hinged member connected to the channel rails.

Referring to the drawings, 1 indicates a 35 casing cylinder which is mounted in a suitable hole or well formed in the ground or in a concrete structure and which is threaded at its upper end there adapted to engage a cylindrical bed casting and guiding sleeve 2. This sleeve member is provided with a horizontal flange 3 which is bolted to a bed plate 4 which is mounted upon an 40 abutment of the concrete in the well.

Within the cylinder 1 and closely fitting the sleeve 2 is a vertically reciprocable hollow piston cylinder 5 having a closed upper end provided preferably centrally thereof 45 with a threaded opening to receive a threaded plug 5'. A packing 6 embraces this piston and is held tightly against the same by means of a gland 7 bolted to the ring 8.

50 Detachably clamped to the upper part of the piston 5 is a two-part casting 9 constituting an attaching member for the vehicle support which consists of two channel rails 10. These channel rails are bolted to the attaching member 9. They extend laterally

from the hollow piston on opposite sides 55 thereof and are spaced apart a suitable width to receive the wheels of the ordinary motor vehicle. These rails are secured only to the head carried by the centrally mounted piston and they extend freely from said 60 central support without other means of bracing or supporting means beneath the same throughout their full extent so as to leave a free, unobstructed space beneath the vehicle supporting rails whereby ready access is afforded to the vehicle. By this arrangement, the vehicle is adapted to be supported in equipoise by the parts of the 65 supporting members extending freely from the center and by means of the central, 70 single piston only. At each end of these rails there is provided a hinged member 11 which may be lowered to provide an inclined track to facilitate the rolling of the vehicle upon the rails and which may be 75 supported in raised position to constitute a stop to prevent the vehicle from rolling from the rails after it has been placed thereon. Pawls 12 serve to hold the hinged 80 members in upright position. The rails on their under sides are preferably provided with blocks 13 to constitute stops to space the rails from the ground when the vehicle is lowered so as to prevent crushing of the 85 hands of the operator in such operation.

The hollow piston is adapted to be elevated so as to lift the vehicle support and the vehicle by means of fluid pressure admitted to the hollow casing 1 and to the interior of the piston. To this end, a pipe 14 leads to the cylinder 1 from an oil supply tank 15. An adjusting valve 16 is located between the cylinder 1 and the tank 15. From the upper part of the tank 15 a pipe 17 leads to a suitable source of fluid 95 pressure, said pipe being controlled by an admission valve 19 adapted to admit the fluid under pressure in order to lift the vehicle and also controlled by a relief valve 20 which is adapted to relieve the pressure 100 in order to permit lowering of the vehicle.

The lower end of the piston 5 is provided with an exterior collar 21 which is adapted to contact with a shoulder 22 formed on the lower end of the sleeve 2 to thereby limit the upward movement of the piston and prevent it from being carried 11 out of the sleeve in the lifting movement.

The piston is free to float on the oil in the cylinder 1 and in the piston, and in consequence thereof may freely rotate around its axis whereby the supporting rails may be employed as a turn-table to permit the vehicle to be swung around to different positions to enable ready access to all parts thereof to be obtained without the necessity of the mechanic changing his position, while 5 at the same time the weight of the vehicle is balanced on opposite sides of the piston so that only one lifting piston need be employed.

In operation, the piston, cylinder and oil tank 15 being filled with oil, when it is desired to elevate the vehicle which has been run upon the rails, the valve 19 is opened so as to admit the fluid under pressure to the tank 15 so as to force oil from the tank into 15 the casing and against the upper end of the piston thus elevating the latter and lifting the vehicle to the desired height. When it occasionally becomes desirable to replace the oil in the cylinder and piston, the plug 20 25 5' may be removed and pressure fluid introduced as when raising the rails, whereby the greater portion of the oil will be blown out through the opening in the piston head.

Having thus described my invention, what

30 I claim is:

1. A vehicle lifting device having a fixed casing cylinder, a source of fluid pressure in communication therewith, a hollow piston mounted in said cylinder, a member detachably secured to the upper end of the piston, and rails secured to said member and extending laterally and equally on opposite sides of said piston for supporting a vehicle.

40 2. A vehicle lifting device comprising a hollow casing, means for admitting fluid pressure thereto, a single, vertically movable and rotatable piston mounted in said casing, vehicle supporting means mounted on said piston, and a stop on said piston for limiting the upward movement thereof.

3. A vehicle lifting device comprising a vertical cylinder, a piston mounted to reciprocate therein, means for supplying fluid pressure to said cylinder to lift said piston, a supporting member carried by the upper end of said piston, and a pair of spaced parallel rails arranged on opposite sides of said supporting member, said member being 50 55 provided with outwardly diverging portions secured at their ends to said rails near the centers thereof, said rails being relatively long and free from extraneous elements from their ends to the diverging portions 60 of said supporting member.

4. A vehicle lifting device comprising a vertical cylinder, a piston mounted to reciprocate therein, means for supplying fluid pressure to said cylinder to lift said piston, 65 a supporting member carried by the upper

end of said piston, and a pair of spaced parallel rails arranged on opposite sides of said supporting member, the sides of said supporting member being arranged beneath and secured to said rails near their centers, 70 said supporting member, centrally of and parallel to said rails being relatively short, said rails being relatively long and free from extraneous elements from their ends to the diverging portions of said supporting member. 75

5. A device constructed in accordance with claim 4 wherein said supporting member comprises a pair of complementary portions, divided transversely of said rails and adapted to be clamped about the upper end 80 of said piston.

6. A vehicle lifting device comprising a vertical cylinder open at its upper end, a hollow reciprocating piston mounted in said cylinder and projecting from the open end thereof, said piston being open at its lower end and closed at its upper end and provided adjacent its upper end with an opening, removable means normally closing said opening, said cylinder and piston being adapted to contain a liquid and means for supplying fluid pressure to the liquid to lift said piston. 90

7. A vehicle lifting device comprising a vertical cylinder adapted to be embedded in the earth and provided with an open upper end, a piston mounted to reciprocate in said cylinder and projecting from the upper end thereof, a gland secured to the upper end of said cylinder and surrounding said piston, the surface of the earth in which said cylinder is embedded being provided with a relatively small shallow depression in which said gland is arranged, means for supplying fluid pressure to said cylinder to lift said piston, a support carried by the upper end of said piston, and spaced parallel rails secured to said support, said rails projecting a substantial distance beyond said depression and being supported on the surface of the earth when said piston is in lowered position. 100 105 110

8. A vehicle lifting device comprising a vertical cylinder, a piston mounted to reciprocate in said cylinder, the lower end of said cylinder being slightly greater in diameter than said piston, the upper end of said cylinder being of the same diameter as and adapted to snugly receive said piston, a projection carried by the lower end of said piston and extending outwardly therefrom, means for supporting a vehicle on the upper end of said piston, and means for supplying fluid pressure to said cylinder to lift said piston. 115 120 125

9. A vehicle lifting device comprising a vertical cylinder, a tubular piston mounted to reciprocate in said cylinder and having a closed upper end, the lower end of said cyl-

inder being slightly greater in diameter than said piston, the upper end of said cylinder being of the same diameter as and adapted to snugly receive said piston, the lower end of said piston being open, means for supporting a vehicle on the upper end of said piston, said cylinder and said piston

being adapted to contain a liquid and means for introducing fluid pressure between the walls of said piston and the lower end of said cylinder.

In testimony whereof I affix my signature.

PETER J. LUNATI.
